UNITED STATES PATENT OFFICE.

PATRICK FLINN, DECEASED, OF LOWELL, MASSACHUSETTS; BY ABEL T. AETHERTON, ADMINISTRATOR.

SAD-IRON HEATER.

Specification forming part of Letters Patent No. 57,055, dated August 7, 1866.

To all whom it may concern:

Be it known that I, PATRICK FLINN, of Lowell, in the county of Middlesex and State of Massachusetts, have invented new and useful Improvements in Sad-Irons; and I do hereby declare that the following is a full and exact description thereof, reference being had to the accompanying drawings, and to the letters of reference marked thereon.

The nature of my invention consists in the arrangement and construction of the pillars, making a solid connection of the top and bottom plates, fire-box, back flues, and flattened perforated gas-pipe inclosed with wire-gauze, as hereinafter set forth.

To enable others skilled in the art to make and use my invention, I will proceed to describe its construction and operation.

Figure 1 represents a plan of a pillar sad-iron. Fig. 2 represents a plan of the same with the top off. Fig. 3 represents a longitudinal section. Fig. 4 represents a section through A and B of Fig. 1. Fig. 5 represents a back-end elevation.

a represents the handle; *b*, the chimney; *r*, the outlet of the chimney; *s*, the draft-holes; *c*, the non-conducting hand-fender; *d*, the top plate; *e*, the air-chamber; *f*, the top plate of the fire-box; *g*, the bottom plate of the fire-box; *h h*, the sides; *j j j*, the pillars, with their angles facing the center; *k*, the wire-gauze; *l*, the flattened perforated gas-pipe; *m*, the rubber tube; *n n*, the spiral springs; *o*, the center flue, and *p p*, the side flues.

The operator, after attaching the end of the

rubber tube *m* at *q* to the supply gas-pipe, the gas let on, the lighted match applied to the center flue, *o*, instantly ignites the gas which escapes from the flattened perforated gas-pipe *l*. The heat is evenly diffused and distributed over the entire interior of the fire-box by the aid of the top-plate, *f*, of the fire-box, which plate *f* is so constructed that it throws the flames against and between the pillars *j j j*. The pillars *j j j* being instantly heated thereby the heat is imparted at once to the top and bottom plates, *f* and *g*, of the fire-box and the sides *h h*, the wire-gauze *k* acting as an agent to consume the smoke and soot.

The flues *o* and *p p* act as feeders to supply the burning gas with the required quantity of oxygen. The air-chamber *e* and fender *c* serve as non-conductors, keeping the heat from the handle *a*. The chimney *b* and holes *s* give the needed draft. The spiral springs *n n* prevent the rubber tube *m* from collapsing where it connects with the supply gas-pipe at *q* and gas-pipe *l*.

What I claim as my invention, and desire to secure by Letters Patent, is—

1. The angular pillars *j j j*, in solid connection with the top plate, *f*, of the fire-box to the bottom plate, *g*, as herein described.

2. The top plate, *f*, of the fire-box, so constructed as to throw the flame of gas as herein described.

PATRICK FLINN.
